CURTAIN ROD HOLDER

Nicholas Puppo, Chicago, and John Chidichimo,
Cicero, Ill.

Application July 25, 1938, Serial No. 221,154

4 Claims. (Cl. 248—261)

This invention relates to curtain rod holder and more particularly to displaceable curtain rod supports, although certain features thereof may be employed with equal advantage for other purposes.

It contemplates more especially the provision of a curtain rod supporting bracket that has a displaceable element for carrying the rod so as to retain such in normal operative position or 10 permit the descent thereof for curtain replacement.

The problem of hanging curtains has always proved to be a difficult one for the housewife in that the curtain rods are elevated appreciably above the normal reach of the average individual. This necessitates the use of a stepladder in the home that is always precarious to most individuals in climbing and retaining themselves balanced in a perched position above the 15 normal floor level. Many serious accidents have been occasioned by the requirement of hanging or re-hanging curtains so that the provision of expedients for lowering the curtain rod without resort to a stepladder or other requirement 20 to assume an elevated position of support, is deemed to be an important safety device as well as provide for more effective and simplified curtain hanging facilities for elimination of many 25 of the hazardous curtain hanging requirements 30 of the past.

One object of the present invention is to simplify the construction and improve the operation of devices of the character mentioned.

Another object is to provide an improved curtain rod holder that is displaceable to a level within reach of the average housewife or individual required to hang curtains.

Still another object is to provide an improved curtain holder that is capable of displacement 40 from its normal position of support to render such accessible to an attendant without requiring the use of a stepladder or other expedient for assuming an elevated position.

A further object is to provide a curtain rod 45 holder bracket that has a displaceable curtain rod support which can be retained in its elevated normal curtain hanging position or permitted to descend within the reach of an individual of average stature.

Still a further object is to provide an improved curtain rod holder having improved means for retaining such in its elevated position or permitting its displacement to its lowered position.

A still further object is to provide an improved 50 curtain rod holder that is displaceable to normal

hanging and lowered replacement position to render such easily accessible for curtain replacement.

Other objects and advantages will appear from the following description of an illustrative embodiment of the present invention.

In the drawing:

Figure 1 is a fragmentary front view in elevation of a window casing showing a curtain rod holder attachment embodying features of the 10 present invention, it being shown in its lowered displaced position within the reach of an individual of average stature.

Figure 2 is a side view in elevation of the device shown in Figure 1, the window casing being 15 shown in section to clarify the showing.

Figure 3 is an enlarged fragmentary front view in elevation of a retaining clip constituting a component element of the structure shown in Figures 1 and 2.

Figure 4 is a sectional view taken substantially along line IV—IV of Figures 1 and 3 when the curtain rod holder is in its upwardly collapsed normal hanging position.

Figure 5 is a sectional view taken substantially 25 along line V—V of Figure 1.

Figure 6 is a sectional view taken substantially along line VI—VI of Figure 1.

Figure 7 is a sectional view taken substantially along line VII—VII of Figure 1.

Figure 8 is a fragmentary broken view in elevation of the rod which is used in actuating the retainer clip shown in Figure 3 and illustrated in aligned operative position therewith.

Figure 9 is a plan view of the collapsed device 35 shown in Figure 1, the window casing being shown in broken outline.

Figure 10 is a front view in elevation of a modified device showing the type of structure used in conjunction with an unusually wide curtain 40 holder.

The structure selected for illustration is shown attached to the usual window frame 10 having an opening 11 therein for receiving the customary window pane 12. Window curtains are usually substantially so as to cover the window pane 12 and overlap the window casing 10 so as to provide a decorative covering therefor without appreciably obstructing the light normally passing therethrough. An elongated and comparatively 50 thin metallic strip 13 is disposed horizontally and provided with a plurality of apertures 14 therealong for the reception of fasteners such as screws 15, serving as an attaching expedient for the metallic strip 13 above the window pane 12 in 55

a position normally occupied by a curtain rod when properly suspended relative to the casing 10.

The strip 13, is in this instance, provided with confronting pairs of links 16-17 and 18-19 that are interconnected as at 20 and 21 so as to render such pivotal for extension and collapsing relative to each other. The lower links 17-19 are pivotally connected as at 22 so as to form a substantially diamond-shaped linkage in its displaced position and to permit their collapsing in superposed relation by virtue of the end attachment of the links 16-18 to the horizontal metallic strip 13 proximate to the center thereof, this being effected by means of pins 23 and 24 that serve to render the links 16-17 and 18-19 collapsible relative to each other in a displaceable position of alignment with the metallic strip 13 that is attached to the window casing 10.

In order to carry the curtain rod holder metallic strip 25 corresponding in width with or somewhat wider than the metallic attaching strip 13, it is carried by the links 17-19 in the horizontally disposed position for support and displacement relative to the horizontal window casing attaching strip 13. This is accomplished by links 26 and 27 that are pivotally connected to substantially the head portion of the lower links 17-19 by means of pivotal pins 28 and 29 so as to carry over the clips 30 that are pivotally connected by means of a pin 31 to the extremities of the links 26-27, the clips 30 being spaced therefrom by means of a collar 32 provided to laterally offset that permits the curtain rod holder strip 25 to assume a position immediately above the links 26-27 when collapsed in superposed relation with the links 17-19, 16-18, and the window attaching strip 13.

Similarly threaded clips 30 are pivotally connected and spaced relative to the lower links 17-19 proximate to their point of interconnection 22 so as to support the curtain rod holder strip 25 in a horizontal position in parallel relation with the window attaching strip 13. In order to govern the displacement of the metallic clips 30 that are attached to the lower regions of the links 17-19 between the necessary elements to afford the collapsing and extension of the curtain rod holder strip 25 relative to the window attaching strip 13, inwardly directed depressions 33, in this instance four, are stamped or otherwise impressed in the curtain rod supporting strip 25 on both sides of the normal positions of the threaded clips 30.

Consequently, the lower ends of the links 17-19 are movable in alignment with the curtain rod holder strip 25 or displaced therebelow as shown in Figure 1 to assume an operative or inoperative position depending upon the requirements of supporting curtains in their normal position or to render them accessible for replacement. So that the lower links 17-19 will not be displaced out of alignment with the links 26-27 and to collapse such in alignment with the curtain rod strip 25, the links 17-19 are provided with downwardly directed hooks 34 that are stamped or otherwise formed from the material thereof to provide the cut-outs 35 (Figure 5). In consequence thereof, the hooks 34 on the links 17-19 actuate the upper edges of the links 26-27 when displaced thereover in alignment therewith.

This also insures that the lower curtain rod holder strip will assume a position that is in superposed alignment with the links 26-27 and

17-19 when collapsed relative to each other. Similarly, the window casing attaching strip is provided with downwardly depending hooks 34 that are stamped from the material thereof to engage the upper edges of the links 16-17 to limit their displacement in superposed alignment therewith. It will be apparent, therefore, that the curtain rod holder strip can be displaced upwardly in substantial alignment with the window attaching strip 13 so that the intermediate links 16-18, 17-19, and 26-27 are interposed between the curtain rod holder strip and the window attaching strip 13 collapsed for alignment with each other.

The curtain rod holder strip 35 is preferably provided with normally disposed confronting brackets 36 and 37 welded or otherwise joined to the extremities thereof to support substantially U-shaped curtain rod sockets 38, in this instance two, on each of the brackets 36-37. Curtain supporting rods 39 and 40 may be disposed in the sockets 38 that confront each other on the brackets 36-37 for support in alignment with the strip 25 that is displaceable to a position in alignment with the window attaching strip 13 or may be lowered within easy reach of the individual to effect adjustment, replacement, or the dusting thereof without any requirement to assume a precarious perched position on a stepladder or other elevated support- 30 ing platform.

In order to retain the curtain rod strip 25 in normally aligned position with the window attaching strip 13 against accidental descent or displacement so that the interposed links are collapsed relative to each other, a resilient clip 41 is riveted, soldered or welded to the center of the window attaching strip 13 so as to present a reversely bent extremity 42 having an inwardly directed arcuate terminus 43 that is yieldingly supported by the reversely bent portion 41 of the clip 41. A complementary clip 44 is mounted for support on the pivot 22 that interconnects the links 17-19. The clip 44 has an arcuate extremity 45 along the upper edge thereof to confront and interconnect the resiliently mounted terminus 43 of the upper clip 41, thereby effecting interengagement therebetween (Figure 4) and procuring the accidental lowering of the strip 25 with its curtain rods 39-40 supported 50 thereon.

As shown, the lower clip 44 has a tubular depending extremity 46 that is telescopically engageable by the reduced extremity 47 of a releasing rod 48. The releasing rod 48 is positioned 55 with its reduced extremity 47 telescoped within the extremity 46 of the lower clip 44 so as to enable the rotary displacement thereof (see dotted outline in Figure 3) and permit the arcuate terminus 45 thereof to be disposed out of alignment with the arcuate terminus 43 of the upper clip 41, thereby permitting the lowering of the curtain rod holder strip 25 to a position within easy reach of the housewife or other attendant called upon to dust, remove or replace the curtains supported on the rods 39-40.

It will be apparent, therefore, that a very inexpensive, simple, and practical curtain rod holder has been provided that can be readily displaced to a position within easy reach for 70 mounting or removal of the curtains therefrom and displaced to its normal position above the window pane 12 without requiring the attendant to become perched on an elevated platform in a hazardous position. Where the curtain rods 75

are needed for unusually wide windows 10, or a series of closely adjacent windows, the same structural arrangement would be utilized in conjunction with additional interconnected links 49-50 and 51-52 (Figure 10) that correspond with and are spaced from the links 13'-17' and 18'-19' (Figure 1) described in connection with the previous embodiment.

The interconnected links 49-50 and 51-52 are provided with links 26" and 27" that correspond with the links 26' and 27' interconnected to the lower links 17'-19' which have been (Figure 10) fully described and illustrated in connection with the previous embodiment (Figure 1). These links carry the threaded extremity clips 30" at their extremities for displacement along the curtain rod holder strip 25' in a manner described in connection with the links 27', 19', 26', and 27' fully described in the previous embodiment (Figure 1). It will be observed, therefore, that the additional interconnected links 49-50 and 50-51 merely serve to support an appreciably longer window attaching strip 13' and corresponding curtain rod holder strip 25' that are necessary in connection with unusually wide windows or a battery of adjacent disposed windows while curtain rod holders may be mounted in the manner described supra.

Various changes may be made in the invention herein specifically described without departing from or sacrificing any of the advantages of the invention or any features thereof, and nothing herein shall be construed as limitations of the invention, its structural concept or embodiment as to the whole or any part thereof except as defined in the appended claims.

We claim:

1. In a displaceable curtain rod support, the combination with an elongated fixed flat strap 40 for attachment to a window frame, of an elongated movable flat strap for sustaining a curtain rod, said straps being of comparative thinness relative to their width, comparatively shorter flat lever means interposed between said elongated fixed and movable flat straps to enable the compactly aligned or relatively displaced positioning thereof in relation to said elongated flat straps, means on one of said elongated flat straps in the path of the other of said elongated flat straps to limit the upward displacement of said movable strap relative to said fixed strap, resilient fastener means on one of said elongated straps, and complementary fastener means on the other of said elongated straps for connecting and disconnecting said complementary resilient fastener to maintain said elongated movable flat strap in operative aligned relation with said elongated fixed strap and permit relative downward gravitation relative to said elongated fixed strap.

2. In a displaceable curtain rod support, the combination with an elongated fixed flat strap for attachment to a window frame, of an elongated movable flat strap for sustaining a curtain rod, said straps being of comparative thinness relative to their width, a plurality of pivotally connected flat means interposed between said elongated fixed movable flat straps to enable the compactly aligned or relatively displaced positioning thereof for spaced connection along the length of said elongated movable strap, said flat link means being pivotally connected to said elongated fixed flat strap and slidably associated with said elongated movable flat strap, means on one of said elongated flat straps in the path of the other of said elongated flat straps to limit the upward displacement of said movable strap relative to said fixed strap, flat resilient fastener means having an arcuate spring clip pivotally mounted on one of said elongated straps, complementary fastener means having an arcuate spring clip on the other of said elongated straps for connecting and disconnecting said resilient fastener complementary means depending upon its pivotal position to maintain said elongated movable flat strap in operative aligned relation with said elongated fixed strap and permit relative downward gravitation relative to said elongated fixed strap, and flat link means pivotally connected to said elongated fixed flat strap and slidably associated with said elongated movable flat strap.

path of the other of said elongated flat straps to limit the upward displacement of said movable strap relative to said fixed strap, resilient fastener means pivotally mounted on one of said elongated straps, and complementary fastener means on the other of said elongated straps for connecting and disconnecting said complementary resilient fastener means depending upon its pivotal position to maintain said elongated movable flat strap in operative aligned relation with said elongated fixed strap and permit relative downward gravitation relative to said elongated fixed strap.

3. In a displaceable curtain rod support, the combination with an elongated fixed flat strap 15 for attachment to a window frame, of an elongated movable flat strap for sustaining a curtain rod, said straps being of comparative thinness relative to their width, comparatively shorter flat lever means interposed between 20 said elongated fixed and movable flat straps to enable the compactly aligned or relatively displaced positioning thereof in relation to said elongated flat straps, means on one of said elongated flat straps in the path of the other 25 of said elongated flat straps to limit the upward displacement of said movable strap relative to said fixed strap, resilient fastener means on one of said elongated straps, complementary fastener means on the other of said elongated straps interengaging arcuate spring clips on both of said fastener means for connecting and disconnecting said resilient fastener complementary means to maintain said elongated movable flat strap in operative aligned relation with said elongated fixed 30 strap and permit relative downward gravitation relative to said elongated fixed strap, and flat lever means pivotally connected to said elongated fixed flat strap and slidably associated with said elongated movable flat strap.

4. In a displaceable curtain rod support, the combination with an elongated fixed flat strap for attachment to a window frame, of an elongated movable flat strap for sustaining a curtain rod, said straps being of comparative thinness 45 relative to their width, a plurality of pivotally connected flat means interposed between said elongated fixed and movable flat straps to enable the compactly aligned or relatively displaced positioning thereof for spaced connection along the 50 length of said elongated movable strap, said flat link means being pivotally connected to said elongated fixed flat strap and slidably associated with said elongated movable flat strap, means on one of said elongated flat straps in the path of the other of said elongated flat straps to limit the upward displacement of said movable strap relative to said fixed strap, flat resilient fastener means having an arcuate spring clip pivotally mounted on one of said elongated straps, complementary 55 fastener means having an arcuate spring clip on the other of said elongated straps for connecting and disconnecting said resilient fastener complementary means depending upon its pivotal position to maintain said elongated movable flat strap in operative aligned relation with said elongated fixed strap and permit relative downward 60 gravitation relative to said elongated fixed strap, and flat link means pivotally connected to said elongated fixed flat strap and slidably associated with said elongated movable flat strap.
